HYDRAULIC MOTOR SYSTEM AND COOLING
MEANS FOR THE PUMP THEREOFThomas F. Stacy, Piqua, Ohio, assignor to The
French Oil Mill Machinery Company, Piqua,
Ohio

Application May 27, 1944, Serial No. 537,565

14 Claims. (Cl. 60—52)

1

This invention relates to hydraulic motors and is in the nature of an improvement upon my prior copending application, Serial No. 492,526, filed June 28, 1943, to which reference may be had for a more complete disclosure of the hydraulic motor and an operating system therefor.

In operating systems for hydraulic motors, such as presses, variable delivery pumps are extensively employed for supplying the operating fluid to the motors, and such pumps are frequently operating under substantial pressures for substantial periods of time, which tends to cause heating of the operating oil and of the main pump, particularly if the rate of delivery or fluid flow through that pump is curtailed to a substantial extent.

One of the objects of the invention is to provide improved means for cooling the main pump in a manner to prevent it from overheating and thereby to reduce wear on the parts of the pump, and to prevent an undesired temperature rise in the operating oil or fluid for the hydraulic motor.

In modern hydraulic presses, it is becoming quite common practice to dispose the reservoir at the top of the press, and many of the operating and control equipment and parts, such as valves, pumps, and other mechanism of the controls within, or above the reservoir for surplus operating fluid or oil, and also to include within or just above the reservoir as many as possible of the pipes and connections between the pump, the valves and the controls, so that leakage will always be into the reservoir, where it will be harmless.

Another object of the invention is to provide an improved arrangement by which access may be easily had to the valves, pumps, pipes and other mechanism within a reservoir when servicing of those parts is necessary, and with which the reservoir may be easily and quickly emptied or refilled in a simple manner, and without extra pumps and apparatus whenever desired.

Another object of the invention is to provide an improved operating system for a hydraulic motor by which overheating of the main pump may be prevented; with which a pilot fluid under pressure will be available with a desired minimum pressure at all times to operate controls for the hydraulic motor; with which the valves, pumps and other operating parts and much of the piping may be disposed within or just above a reservoir for the operating fluid, and such pipes, valves and pumps made easily accessible for servicing and repairs whenever necessary; and which will utilize a minimum of apparatus and parts.

Another object of the invention is to provide

improved means by which much of the same mechanism may be used to cool the main pump and to empty or refill the operating reservoir in which parts of the operating or control mechanism for the hydraulic motor may be disposed.

A further object of the invention is to provide an improved hydraulic system by which each of the above objects may be accomplished; which will require a minimum of additional apparatus; and which will be compact, dependable, simple and inexpensive.

Other objects and advantages will be apparent from the following description of an embodiment of the invention, and the novel features will be particularly pointed out hereinafter in connection with the appended claims.

In the accompanying drawings:

Fig. 1 is a plan of the upper end of a hydraulic motor with controls and operating mechanism applied thereto, and constructed in accordance with this invention.

Fig. 2 is a face elevation of one form of a variable delivery, reversible type of hydraulic pump which may be advantageously employed for operating a hydraulic motor in the apparatus of Fig. 1.

Fig. 3 is a side elevation of a portion of the apparatus shown in Fig. 1, but with parts broken away to show interior parts, particularly with respect to the arrangement of the piping and certain of the valves; and

Fig. 4 is a schematic diagram illustrating a simple operating hydraulic circuit for the hydraulic motor and the manner in which this invention may be applied thereto.

In the illustrated embodiment of the invention, the hydraulic motor, for the control of which the system is designed, may be of any suitable type, but that disclosed in my copending application, Ser. No. 492,526, above identified, is the type illustrated in the drawings.

In apparatus of this type, the reservoir for the working fluid, such as oil, the pumps and the controls are all disposed at the top of the press. The pumps, the valves, controls and piping are also largely disposed within or just above the reservoir, so that any leakage will drain directly into the tank. In such cases it is desirable to be able to empty the reservoir when servicing the pumps, valves and piping is desired. Accordingly, the usual reservoir is replaced by two separate reservoirs, an upper or top reservoir 10 (Fig. 3), and a lower or auxiliary reservoir 11, both of which are above the hydraulic motor.

The upper or top reservoir 10 is the normal

or working reservoir in which as many as possible of the operating parts, such as the pump, valves and much of the piping are located. A pipe 12 opens from the bottom of the top reservoir 10 into the lower reservoir 11, and is provided with a valve 13 which is normally closed but may be opened in order to drain oil from the top reservoir 10 into the lower reservoir 11, when one desires to have access to the mechanism disposed within the top reservoir 10. The valve 13 is normally closed except when one desires to empty the top reservoir.

Disposed within the top reservoir 10 is a main pump 14 which has its operating or pump shaft extending through a packed opening or gland in a wall 15 of the reservoir 10, and outside of the reservoir 10, the pump is connected through a flexible drive 16 with a shaft 17 of an electric motor 18 or other suitable prime mover for the pump 14. This pump 14 may be of any suitable type, but it is preferably of the variable displacement or variable delivery type, such as may be set or adjusted to create and maintain a desired pressure, even though no appreciable amount of fluid is passing through the pump. The pressures in such pumps are frequently very high, and overheating of the pump becomes a problem.

The showing of the pump 14 in Fig. 1 is more or less diagrammatic, but in Fig. 2 I have shown an elevation or face view of a pump 14 of a suitable type which can be used successfully as the main pump to operate the hydraulic motor. This type of pump is known as a radial piston, variable delivery reversible pump, and it has a plurality of radially disposed pistons. Its pump shaft 14a is connected to the flexible coupling 16 at one end, and at its other end it extends into the pump housing to operate the movable parts of the pump. This particular type of pump has a relatively stationary pintle aligned with the shaft, through which communication may be had with the radial cylinders, and conduits extend from the openings in the pintle to positions near the periphery of the pump housing, where they open into pipes 19 and 20.

Pumps of this type have a floating or shiftable member which, when in central position, disposes the cylinders and pistons concentrically about the axis of rotation of the shaft 14a, so that the pump will not deliver fluid under pressure in either direction. By shifting this floating member to one side into a position of eccentricity, it causes delivery of fluid through one pipe, such as the pipe 19, and creates a suction in the other pipe, such as the pipe 20. When it is shifted in the other direction to the other side of its central position, or into an opposite position of eccentricity, it makes a suction pipe of the pipe 19 and delivers fluid under pressure through the pipe 20. Because of this characteristic, these pumps are also commonly known as reversible, variable delivery pumps, but they can be used as unidirectional delivery pumps.

The pump 14 has a closed housing, with a chamber 21 therein around the movable parts and the radial cylinders, and a pipe 22 is connected through the pump housing into the lower part of this chamber 21. An outlet pipe 23 is connected into the upper part of the housing to communicate with this chamber 21.

Also disposed in the upper reservoir 10 is an auxiliary pump 24, such as a rotary vane type pump, secured to the wall 15 of the reservoir, and with its operating shaft 25 extending outwardly through the wall 15 where it is connected through a flexible coupling to the shaft of an

electric motor 26 by which the pump 24 may be continuously driven. The intake side of the pump 24 (see Fig. 3), is connected to a pipe 27, which extends outside of the reservoir 10 and connects to a valve 28, one branch of which is connected by a pipe 29 to a filter 30 disposed in the lower part of the top reservoir 10. The other branch of the valve 28 is connected by a pipe 31 to a filter 32 disposed in the lower part of the lower reservoir 11. By operating the valve 28, the intake pipe 27 of the pump 24 may be connected alternately and selectively to the lower part of either of the reservoirs 10 and 11.

The output side of the pump 24 is connected by a pipe 33 to a choke or pressure relief valve 34, which is in the nature of a pressure relief valve and creates a minimum back pressure on the pump 24. This choke 34 is within the top reservoir 10, but it has an outlet extending through the wall 15 of the reservoir and then is connected by an elbow 35 to a filter 36, the other side of which is connected by pipe 37 to one end of one channel through a heat exchanger 38. The other end of that channel extends through a side wall of the top reservoir 10, where it is connected to the pipe 22 that leads to the lower end of the chamber of the pump housing (see Fig. 2). The pipe 23 at the top of the pump discharges back into the reservoir 10.

From the foregoing, it will be observed that the pump 24 withdraws fluid from the upper reservoir 10, delivers it through the choke 34 to the filter 36, then through one channel of the heat exchanger 38 to the chamber in the pump housing, and from the pump housing it is returned to the reservoir 10. The other and separate channel of the heat exchanger 38 is provided with connections 39 and 40 by which a heat exchange medium, such as cooling water, may be passed in heat exchange relation to the fluid received through the pipe 37 and delivered into the pipe 22. Heat exchangers of this type are well known in the art, and therefore the details are not illustrated.

Included in one of the pipes 39 and 40 is a flow regulator 41 (Fig. 1), and in this illustrated example, this regulator is in series with the pipe 40, so that all of the cooling water or suitable heat exchange medium must flow through this regulator in an amount determined by the setting of the regulator. These flow regulators are also well known in the art, and their details have not been illustrated, but they have a valve member therein which is operated by fluid pressure created in a duct 42. This duct extends through a side wall of the reservoir 10 and terminates in a thermal cell 43 disposed within the reservoir 10. The varying temperature in the reservoir 10 will produce a varying fluid pressure in the cell 43 and duct 42, which causes the valve in the flow regulator to open or close to different extents, and thereby controls the rate of flow of the cooling water or heat exchange medium through the exchanger 38. Thus, the fluid delivered through the housing of the pump 14 will have its temperature controlled by operation of the flow regulator, which in turn, is controlled by the temperature of the oil or fluid in the reservoir 10.

The pipe 33 on the output side of the pump 24 has a duct 44 which leads to the pilot-operated controls for the hydraulic motor, so that there will always be a fluid under a minimum pressure available for pilot operation of the controls of the hydraulic motor. A simple hydraulic system

utilizing this invention is shown diagrammatically in Fig. 4.

The particular manner in which the pump 14 operates the hydraulic motor is not material to this invention, and any system of pilot-operated controls for the ram or hydraulic motor may be employed. In Fig. 4 a simple hydraulic system with motor and pilot operation of the controls is illustrated diagrammatically, but it will be understood that if desired a more elaborate system and controls, such as is disclosed in my co-pending application Serial No. 492,526, hereinabove identified, may be employed.

In this simple form and diagram shown in Fig. 4, the main pump 14 operates to deliver fluid always in the same direction, and functions as a unidirectional pump. Its intake pipe 20 is connected to the reservoir 10 so as to draw operating fluid therefrom and deliver it under pressure through the pipe 19 leading to a four-way or reversing valve 45. Pipes 46 and 47 of valve 45 lead respectively to retracting and advancing chambers 48 and 49 in a cylinder 50 to create the hydraulic motor. Separating the retracting and advancing chambers 48 and 49 in a piston 51 sliding closely in the cylinder 50 and having a reduced stem or ram portion 52 extending out of the cylinder 50 from the chamber 48 through a suitable packing gland, and carrying a platen 53 that moves toward and from a base 54, as the piston 51 reciprocates. By operating the valve 45, the fluid under pressure from the pump may be delivered alternately to the motor chambers 48 and 49 so as to move the platen 53 back and forth. The valve 45 may have pilot devices 55 and 56 which operate the valve element in the valve 45 between selected positions, and these pilot devices are supplied with a pilot-operating fluid through pipes 57 and 58 leading from a pilot control valve 59 which, in turn, is supplied with pilot-operating fluid through the pipe 44. The pilot control valve 59 may be operated by a manual lever 60 or in any other suitable manner.

This is an extremely simple system, and often commercial installations have a rather elaborate system of controls, such as for example, providing a control manipulated by the platen when it reaches a desired position in its return movement for setting the valve 45 to a position in which fluid from the pump is by-passed back to the reservoir 10, and at the same time closing the pipe 46 to prevent escape of fluid from the retracting chamber 48. Such systems and controls are well known in the art, and their details have been omitted from this disclosure in order to simplify the description of the device and prevent confusion with the improved controls which form the subject matter of this invention.

The operation of the device is believed to be clear from the foregoing description, but will be briefly summarized. With both pumps 14 and 24 operating continuously, and with the valve 28 set to draw fluid from the reservoir 10 and valve 13 closed, the fluid will be drawn from the reservoir 10 and delivered by the pump 24 under a minimum back pressure, partly to the pilot conduit 44, and the balance through the choke 34, filter 36 and heat exchanger 38 to the chamber 21 of the main operating pump 14, and then back to the reservoir through the pipe 23. When the temperature of the oil increases beyond an undesired extent, the thermal device 43 will open the flow regulator 41, allowing a cooling medium to flow through the heat exchanger from pipe 40 to pipe 39, and cool the oil delivered to the pump 75 to pipe 39, and cool the oil delivered to the pump

chamber. This cooled oil passing through the pump chamber 21 will cool the working parts of the main pump 14 and then return to the reservoir 10. Thus, the temperature of the working parts of the pump 14 will be kept below a desired maximum at all times, and a continuous source of pilot-operating fluid under pressure will be available in the conduit 44. By operating the pilot valve 59, the reversing valve 45 may be operated to cause reciprocations of the platen 53.

If, for any reason, one desires to have access to the pumps, valves and pipes that are contained within the upper reservoir 10, the operation of the main pump 14 is stopped, such as by shutting off its operating motor, and the valve 13 is then opened which allows the fluid to pass by gravity from the reservoir 10 to the reservoir 11. After the servicing has been completed, valve 13 is closed, the pump 24 alone is operated, and the valve 28 is operated to connect the pipe 31 to the pipe 27. The fluid is then withdrawn from the lower reservoir 11 and passed through the chamber 21 of the main pump 14 into the tank 10, which soon transfers all of the fluid from the reservoir 11 back into the reservoir 10. After that has occurred, the valve 28 is operated to reconnect the pipes 27 and 29 and the device is ready for a new operation.

30 A pressure responsive switch 61, Fig. 1, may be connected to elbow 35 so as to be caused to operate if the pressure exceeds a predetermined pressure, and it controls wires of a circuit through a battery 62 and a signal 63. The signal is operated whenever the filter 36 becomes clogged or plugged and increases the back pressure, to warn the attendant that the filter must be cleaned.

40 A temperature responsive switch 64 has a heat responsive cell 65 within the reservoir 10 and it similarly closes a circuit through a danger signal 66 if the temperature of the oil in the reservoir 10 gets too high for any reason.

It will be observed from the foregoing that 45 this transfer of fluid between the reservoirs is accomplished in a relatively simple manner by using gravity or the same pump which supplies the pilot operating fluid and cools the main pump, and at the same time the overheating 50 of the pump is prevented in a simple manner by automatic means. This cooling of the main pump very definitely improves the operation and life of such pumps.

It will be understood that various changes in 55 the details and arrangement of parts, which have been herein described and illustrated in order to explain the nature of the invention, may be made by those skilled in the art within the principle and scope of the invention as expressed in the appended claims.

I claim:

1. In an operating control for a hydraulic motor including said motor with its controls, a main pump with a closed housing enclosing the working elements, a reservoir, and piping connecting the reservoir, pump and motor to form an operating hydraulic system for said motor, that improvement which comprises the combination therewith of an auxiliary pump connected 65 at its intake side to said reservoir, a heat exchanger having a passage in which a fluid may be cooled and connected at one end to the output side of said auxiliary pump and also having another passage through which a cooling medium is passed, a conduit connecting the

other end of said passage of said exchanger to one part of said pump housing to convey the operating fluid from the auxiliary pump that passes through said exchanger to said pump housing, a passage connected to said auxiliary pump and leading to said controls to furnish operative pilot liquid thereto, another conduit connecting the opposite part of said pump housing to said reservoir, and a thermally controlled element responsive to the temperature of the oil in said reservoir for regulating the flow of cooling medium through said exchanger, to pass increased cooling medium through said exchanger with increased temperature of the oil in said reservoir.

2. In an operating control for a hydraulic motor including said motor with its controls, a main pump with a closed housing enclosing the working elements, a reservoir, and piping connecting the reservoir, pump and motor to form an operating hydraulic system for said motor, that improvement which comprises the combination therewith of an auxiliary pump connected at its intake side to said reservoir, a heat exchanger having a passage in which a fluid may be cooled and connected at one end to the output side of said auxiliary pump and also having another passage through which a cooling medium is passed, a conduit connecting the other end of said passage of said exchanger to one part of said pump housing to convey the operating fluid from the auxiliary pump that passes through said exchanger to said pump housing, another conduit connecting the opposite part of said pump housing to said reservoir, a choke in the connection from the auxiliary pump to said exchanger, a take off pipe for supplying fluid under pressure to fluid operated controls for said motor, connected to the output side of said auxiliary pump before its connection to said choke, and a thermally controlled element responsive to the temperature of the oil in said reservoir for regulating the flow of cooling medium through said exchanger, to pass increased cooling medium through said exchanger with increased temperature of the oil in said reservoir.

3. In an operating control for a hydraulic motor including said motor with its controls, a main pump with a closed housing enclosing the working elements, a reservoir, and piping connecting the reservoir, pump and motor to form an operating hydraulic system for said motor, that improvement which comprises the combination therewith of an auxiliary pump connected at its intake side to said reservoir, a heat exchanger connected to the output side of said auxiliary pump, a conduit connecting said exchanger to one part of said pump housing to convey the operating fluid from the auxiliary pump that passes through said exchanger to said pump housing, a passage connecting the output side of said auxiliary pump and said controls to supply thereto operating pilot liquid, another conduit connecting the opposite part of said pump housing to said reservoir, and a regulator for the activity of said exchanger having a heat responsive control element disposed in heat responsive relation to the fluid in said reservoir whereby the activity of said heat exchanger will be automatically responsive to the temperature of the operating fluid in said reservoir.

4. In an operating control for a hydraulic motor including said motor, its controls, and a main pump, that improvement which comprises a working reservoir, a separate storage reservoir,

an auxiliary pump, a branched pipe connecting the intake side of said auxiliary pump to the lower part of each of said reservoirs, a selector valve in said pipe and operating to connect said auxiliary pump alternately and selectively to said reservoirs, a pressure relief valve in the output side of said auxiliary pump for creating a desired back pressure, a pipe leading from the output side of the auxiliary pump before its connection to said relief valve, for supplying operating fluid to said controls, means connected to said relief valve for passing fluid therefrom in heat exchanging relation to said main pump, and then to one of said reservoirs, and means for varying the temperature of the fluid passing from said relief valve to said main pump.

5. In an operating control for a hydraulic motor including said motor, its controls, and a main pump, that improvement which comprises a working reservoir, a separate storage reservoir, an auxiliary pump, a branched pipe connecting the intake side of said auxiliary pump to the lower part of each of said reservoirs, a selector valve in said pipe and operating to connect said auxiliary pump alternately and selectively to said reservoirs, means in the output side of said auxiliary pump for creating a desired back pressure, a pipe leading from the output side of the auxiliary pump before its connection to said means, for supplying operating fluid to said controls, means connected to said previous means for passing fluid therefrom in heat exchanging relation to said main pump and then to one of said reservoirs, means for varying the temperature of the fluid passing from said first means to said main pump, and a pipe directly connecting said reservoirs to drain said one of said reservoirs into the other and having a valve therein for selectively connecting and disconnecting said reservoirs.

6. In a hydraulic system for a hydraulic motor and its controls, a main pump for supplying working fluid to said motor and having a closed housing with a channel around the compressing parts, a reservoir, an auxiliary pump connected at its intake side to said reservoir, means connected to the output side of said auxiliary pump to create a minimum back pressure, a conduit leaving the output side of the pump before its delivery to said means for supplying operating fluid under pressure for the motor controls, a heat exchanger having one channel connected at one end to said means and at its other end to said channel in said housing, the housing having a drain for its channel back to said reservoir, connections to the other channel of said exchanger to enable a cooling medium to be passed therethrough, a regulator in said other channel of said exchanger for controlling fluid flow therethrough, and a thermally responsive element disposed in said reservoir so as to be responsive to the temperature of the operating fluid therein, and controlling said regulator whereby the temperature of said main pump can be controlled and a pilot fluid supplied for operating the controls of said member.

7. In a hydraulic system for a hydraulic motor and its controls, a main pump for supplying working fluid to said motor, and having a closed housing with a chamber in heat exchanging relation to the working parts, and separate from its working compartment, a reservoir, an auxiliary pump connected at its intake side to said reservoir, a heat exchanger having one channel thereof connected at one end to said auxil-

iary pump and at its other end to said chamber of said pump housing, and having its other channel formed for connections by which a heat exchanging medium may be circulated therethrough to modify the temperature of the working fluid delivered by said auxiliary pump, and a flow regulator in said other channel by which the rate of heat exchange with said working fluid delivered to said main pump chamber may be varied, said pump housing having another part of its chamber connected to said reservoir, whereby the fluid delivered by said auxiliary pump will be circulated through said pump housing and returned to said reservoir.

8. In a hydraulic system for a hydraulic motor and its controls, a main pump for supplying working fluid to said motor, and having a closed housing with a chamber in heat exchanging relation to the working parts and separate from its working compartment, a reservoir, an auxiliary pump connected at its intake side to said reservoir, a heat exchanger having one channel thereof connected at one end to said auxiliary pump and at its other end to said chamber of said pump housing, and having its other channel formed for connections by which a heat exchanging medium may be circulated therethrough to modify the temperature of the working fluid delivered by said auxiliary pump, and a flow regulator in said other channel by which the rate of heat exchange with said working fluid delivered to said main pump chamber may be varied, said pump housing having another part of its chamber connected to said reservoir, whereby the fluid delivered by said auxiliary pump will be circulated through said pump housing and returned to said reservoir, said fluid regulator having a thermally responsive, operating element disposed in heat exchanging relation to the fluid passing through said reservoir under the impulsion of said auxiliary pump.

9. In a hydraulic system for a hydraulic motor and its controls, a main pump for supplying working fluid to said motor, and having a closed housing with a chamber in heat exchanging relation to the working parts and separate from its working compartment, a reservoir, an auxiliary pump connected at its intake side to said reservoir, a heat exchanger having one channel thereof connected at one end to said auxiliary pump and at its other end to said chamber of said pump housing, and having its other channel formed for connections by which a heat exchanging medium may be circulated therethrough to modify the temperature of the working fluid delivered by said auxiliary pump, and a flow regulator in said other channel by which the rate of heat exchange with said working fluid delivered to said main pump chamber may be varied, said pump housing having another part of its chamber connected to said reservoir, whereby the fluid delivered by said auxiliary pump will be circulated through said pump housing and returned to said reservoir, said fluid regulator having a thermally responsive, operating element extending into said reservoir so as to operate said flow regulator in response to fluctuations in the temperature of said fluid in said reservoir.

10. In a hydraulic system for a hydraulic motor and its controls, a main pump for supplying working fluid to said motor, and having a closed housing with a chamber in heat exchanging relation to the working parts, and separate from the working compartment, a reservoir, an auxil-

iary pump connected at its intake side to said reservoir, a heat exchanger having one channel thereof connected at one end to said auxiliary pump and at its other end to said chamber of said pump housing, and having its other channel formed for connections by which a heat exchanging medium may be circulated therethrough to modify the temperature of the working fluid delivered by said auxiliary pump, a flow regulator in said other channel by which the rate of heat exchange with said working fluid delivered to said main pump chamber may be varied, said pump housing having another part of its chamber connected to said reservoir, whereby the fluid delivered by said auxiliary pump will be circulated through said pump housing and returned to said reservoir, a filter in series with the channel of said heat exchanger connected to said auxiliary pump, and a pressure responsive switch connected to the connection between said filter and said auxiliary pump, and operated by fluid delivered by the pump if it exceeds a predetermined pressure normally sufficient to cause free circulation of fluid through said pump housing, such as by a high back pressure that might be due to clogging of the filter, and circuit wires controlled by said pressure switch.

11. In a hydraulic system for a hydraulic motor and its controls, a main pump with a working chamber for supplying working fluid to said motor, a pair of reservoirs disposed at different levels, a pipe leading from the upper reservoir to the lower reservoir, a valve in that pipe selectively operable to allow the upper reservoir to drain into the lower reservoir, an auxiliary pump having two connections at its intake side, one to the lower reservoir, and the other to the upper reservoir, a valve operable to connect said auxiliary pump at its intake side alternately and selectively to said reservoirs, a passage connecting the output side of said auxiliary pump to said controls to supply operating pilot liquid thereto, said controls having an exhaust to said upper reservoir, a connection from the output side of said auxiliary pump back to said upper reservoir, whereby fluid may be transferred in either direction between said reservoirs, and a connection between the working chamber of said pump and said upper reservoir whereby said reservoir serves both pumps.

12. In a hydraulic system for a hydraulic motor and its controls, a main pump with a working chamber for supplying working fluid to said motor and a cooling passage therethrough, a pair of reservoirs disposed at different levels, valve controlled means for draining the contents of the upper reservoir into the lower one, an auxiliary pump having two connections at its intake side, one to the lower reservoir, and the other to the upper reservoir, a valve operable to connect said auxiliary pump at its intake side alternately and selectively to said reservoirs, a connection from the output side of said auxiliary pump back to said upper reservoir through said pump cooling passage, whereby fluid may be transferred in either direction between said reservoirs, and a connection between the working chamber of said main pump and said upper reservoir whereby said reservoir serves both pumps.

13. In a hydraulic system having a hydraulic motor, a main pump with a working chamber for supplying working fluid to said motor, a main reservoir having a liquid capacity sufficient

to serve fully said motor and pump, and connections with controls, between the pump, motor and reservoir to form a hydraulic circuit, that improvement which comprises the combination therewith of a second reservoir of sufficient size to receive and hold all of the liquid from said main reservoir and disposed at a lower level than said main reservoir, a valve controlled connection for directly draining the main reservoir into said second reservoir, an auxiliary pump, means for connecting the intake side of said auxiliary pump to the lower parts of said reservoirs alternately, and means connecting the output side of said auxiliary pump to said controls and through said controls to said upper reservoir.

14. In a hydraulic system having a hydraulic motor, a main pump with a working chamber for supplying working fluid to said motor, a main reservoir having a liquid capacity sufficient to serve fully said motor and pump, and connections with controls, between the pump, motor and reservoir to form a hydraulic circuit, that improvement which comprises the combination therewith of a second reservoir of sufficient size to receive and hold all of the liquid from said main reservoir and disposed at a lower level than said main reservoir, a valve controlled connection for directly draining the main reservoir into said second reservoir, an auxiliary pump, means for connecting the intake side of said auxiliary pump to the lower parts of said reservoirs alternately, means connecting the out-

put side of said auxiliary pump to said upper reservoir, a pressure relief valve in said last connecting means for creating a back pressure on said auxiliary pump, and a connection from the 5 output side of the auxiliary pump before said relief valve, for supplying pilot operating fluid to said controls.
